MANUFACTURE OF MOUTHPIECE CIGARETTES

Tom Rowlands, London, England, assignor to Molins Machine Company Limited, London, England, a British company

Filed Jan. 10, 1958, Ser. No. 708,315

Claims priority, application Great Britain Jan. 23, 1957

6 Claims. (Cl. 131—94)

This invention concerns improvements in or relating to the manufacture of mouthpiece cigarettes of the kind which comprise cigarette portions joined to abutting mouthpiece portions by encircling uniting bands.

In the manufacture of such cigarettes, it is usual to assemble cigarette portions and mouthpiece portions into axially aligned groups, to unite them by wrapping adhesive uniting bands about the mouthpiece portions and the end parts of any cigarette portions which abut the mouthpiece portions, and then to sever the united groups at suitable places. Usually a group consists of two cigarette portions with a double-length stub portion between them, and in that case each united group is cut through the mouthpiece portion to produce two mouthpiece cigarettes. The uniting bands may be applied while the groups are moving laterally, for example as disclosed in copending U.S. Patent application Serial No. 671,607, filed July 12, 1957.

It may sometimes happen that for some reason a uniting band fails to be applied to a group, with the result that the group is not united. Further, it may sometimes happen that an incomplete group is assembled, one of the components, such as a mouthpiece portion, having been omitted. It is desirable to be able to detect any of these faults and to reject any such groups before they result in faulty cigarettes.

For the purposes of the present specification, any group which, in the course of manufacture, has passed the stage at which a uniting band has or should have been applied to it to unite it, will be referred to as an "assemblage", and it is to be understood that this term is intended to include not only a complete and united group, but also a group (whether complete or incomplete) to which a uniting band has not been applied or has not been secured, and, in addition, a group (whether united or not) from which a cigarette portion or a mouthpiece portion has been omitted. For convenience an assemblage to which a uniting band has not been secured or has not been applied will be called a non-united assemblage, while an assemblage from which a cigarette portion or mouthpiece portion has been omitted will be called an incomplete assemblage.

According to the present invention there is provided a device for testing assemblages (e.g. in a machine for making mouthpiece cigarettes) comprising a plurality of separate supporting means so arranged as to be operable at different times to support a complete assemblage at different positions along its length. By this arrangement, the component parts of a non-united assemblage will in succession be unsupported and therefore fall away, and the apparatus can be so arranged that an incomplete assemblage will at some stage be unsupported and fall away, whereas a complete, united assemblage will continue to be supported.

The said supporting means may be so positioned and arranged as to support at one time part of a complete assemblage which includes the mouthpiece portion, and at

2

another time parts of the assemblage which consist of cigarette portions. Preferably the device is employed in combination with means for abutting the component parts of a group endwise before they are united, which means are so arranged as to cause an incomplete group to have a shorter overall length than a complete group to be so positioned relatively to the supporting means as to be outside the range of action of at least one of them. For example the supporting means to support the cigarette portions of a complete assemblage may be so positioned as to be capable of engaging such portions only near their extreme ends, and the said positioning means in that case cause an incomplete group, having a short overall length, to be located between the last-mentioned supporting means so that they cannot support it.

The supporting means may comprise suction nozzles operable, during different times, to support assemblages or parts thereof against the action of gravity. For example the device may comprise a rotatable member having peripheral suction nozzles and arranged to transfer assemblages from the apparatus in which they are united to the apparatus on which they are cut. Suction nozzles which engage different parts of an assemblage are put into and out of communication with a source of suction at appropriate different times.

Apparatus in accordance with the invention will now be described by way of example with reference to the accompanying drawings, in which:

Figure 1 is an end view illustrating a testing and transfer device forming part of apparatus for making mouthpiece cigarettes;

Figure 2 is a section on the line II—II, Figure 1;

Figure 3 is a section on the line III—III, Figure 2; and

Figure 4 is a section on the line IV—IV, Figure 2.

The apparatus shown forms part of apparatus for making mouthpiece cigarettes by assembling axially aligned groups, each consisting of two cigarette portions with a double length stub between them, abutting the cigarette portions and stub, and feeding the group sideways into a device whereby the group is rolled over an adhesive uniting band so that the band is wrapped about it. The means for assembling and abutting the groups are in substance the same as those shown in Figures 8 and 10 of the drawings accompanying the complete specification of U.S. Patent No. 2,798,495. In brief, a group is fed endwise until the leading cigarette portion (if present) passes on to a stationary surface against which it is lightly held by a yielding member, such as a spring finger or, as shown in Figure 10 of the drawings of the complete specification just referred to, by a brush. The rear cigarette length is engaged at its rear face by a pusher on an endless chain conveyor, which, through the rear cigarette portion, eventually advances the whole group in timed relationship to the uniting apparatus towards which the group then passes. Due to this arrangement, the group will not be advanced as a whole by the pusher until the rearmost component (which should be a cigarette portion) abuts against the arrested foremost component (which should also be a cigarette portion). If one component is missing, therefore, the remaining two components will be abutted together and fed forwardly together, but they will be fed forward later than the correct time for a complete group, because of the extra distance the pusher has to travel before it can push them forward as a whole. Thus the leading component will not be as far advanced, at a given time, as would be the leading component of a complete group.

In the present case each group is fed lengthwise to a position at which it is engaged by a deflector which moves the group sideways on to a suction drum 1, Figure 1, which holds on its surface, by suction, adhesive uniting bands suitably spaced apart.

The deflector is similar to that disclosed in U.S. patent application Serial No. 671,607, in that whereas the deflector while pushing a group sideways has a forward component of movement (i.e. a component in the direction of endwise movement of the group) it is also provided with a stop member which, during part of its sideways movement with the deflector, has no such forward component. Consequently the endwise movement of a complete group is arrested by the stop member before the group reaches the suction drum 1. If however the group is incomplete, its leading component will, as explained above, not be so far advanced, when the group is engaged by the deflector, as would be the leading component of a complete group. Consequently the incomplete group will continue to move endwise for a longer period than would a complete group, since it reaches the suction drum 1 before it has a chance of reaching the stop member. This explanation will be referred to later.

A concave plate 2 above the drum 1 engages the groups and causes them to roll over the uniting bands and thus to be united.

A suction drum 3 receives the united groups, or assemblages, from the drum 1 and transfers them to a drum 5 on which they are cut in half by a knife 6.

The suction drum 3 in addition to effecting this transfer acts as a testing device whereby non-united or incomplete assemblages can be ejected and not transferred to the cutting drum 5.

The drum 3 is rotatably mounted on a fixed shaft 7, and has formed on it spaced discs 8 which have flutes 9 in their peripheries. Suction nozzles or ports 10 and 10a extend from the surfaces of the flutes to the interior of the drum. Three bearings 11 secured to the inner surface of the drum are provided with holes which form continuations of the ports 10.

The discs 8, and the ports formed in them, are so spaced that if a complete assemblage, of a given size, is received in the flutes, the suction ports 10 in the two middle discs will both register with a part of the assemblage containing the double-length mouthpiece portion, and the ports 10a at the ends of the drum will register with the cigarette portions near their extreme ends.

The shaft 7 is hollow to provide a suction chamber 12, connected to a suitable suction fan or the like (not shown). Conduits 13 and 14 extend from the chamber 12 and can put the chamber into communication with the ports 10 and 10a respectively as the drum 3 rotates. As can be seen from Figure 1, and from a comparison of Figures 3 and 4, the conduits 13 and the conduits 14, respectively, extend outwardly from the chamber in slightly different directions, so that as the drum rotates in the direction shown by the arrow, Figure 1, a pair of ports 10 will register with the conduits 13 before the corresponding ports 10a have come into register with the conduits 14. It will also be seen that the conduits 13 slightly overlap the conduits 14 so that for a short period all the ports 10 and 10a in one row (that is, all the ports extending into one row of flutes in which row an assemblage is to be accommodated) will be in communication with the suction chamber 12.

The shaft 7 is also provided with peripheral grooves 15 which in effect form extensions of the conduits 14 for 45° around the shaft, and thus keep the ports 10a in communication with the suction chamber 12 for some time.

The chamber 12 does not extend quite as far as the left-hand disc 8 (Figure 2), and for this reason the left-hand conduit 14 (as viewed in Figure 2) does not communicate directly with ports 10a, but only through a short channel 16 extending along the shaft 7 and connecting the conduit with the groove 15.

A further chamber 17 is formed within the shaft 7 at its left-hand end as viewed in Figure 2. This chamber communicates, through a radial hole, with a groove 18, Figures 1, 3 and 4, which extends along the length of the shaft and registers with all the ports 10 and 10a

in turn. The chamber 17 is connected to a suitable blowing device (not shown) by which air under pressure is supplied to the chamber for discharge through the ports as they register with the groove 18.

5 The operation of the apparatus is as follows.

Groups each consisting of two cigarette portions with a double-length stub between them and in axial alignment with them are formed and fed endwise, and the parts of each group are brought into endwise abutment, 10 in the manner already described above with reference to U.S. Patent No. 2,798,495. It will be assumed that all the components of a group are present and the group is therefore complete. The abutted group is fed endwise toward a deflecting device which pushes it sideways 15 on to the drum 1, Figure 1. The timing of the abutting and feeding means is such that the group is suitably located on the drum 1 in relation to the flutes and ports in the suction drum 3.

It will further be assumed that a uniting band is correctly applied to and rolled about the group, thus uniting it and forming a complete, united assemblage. This assemblage is then engaged by a row of flutes 9, and is immediately held in those flutes by suction, since at this stage the ports 10 extending from the flutes which hold 25 the mid-portion of the assemblage are in register with the conduits 13. The corresponding ports 10a are not yet in register with the conduits 14, and the assemblage is therefore held suctionally at its mid-portion alone—that is, the portion which contains the double-length 30 mouthpiece portion.

As the drum 3 continues to rotate, carrying the assemblage further from the drum 1, the ports 10 move past the conduits 13, but before this happens the ports 10a are put into communication with the suction chamber 35 through the conduits 14 and the channel 16. Thus when suction is cut off from the mid-portion of the assemblage, suction has already been applied to the extreme ends and the assemblage is still held in the flutes 9. This continues until the assemblage is brought into a flute in the cutting drum 5, the suction being applied meanwhile through the grooves 15, and being cut off when the ports 10a move away from the grooves 15. The assemblage 40 is then carried by the drum 5 past the knife 6 which subdivides it.

45 Considering now a case in which a complete group is fed on to the drum 1, but no uniting band is fed into contact with it, this group will roll on the drum 1 and in due course be delivered to a row of flutes 9 of the suction drum 3, as a non-united assemblage. The double-length mouthpiece portion, which forms the mid-portion 50 of this assemblage, is immediately held by suction acting through ports 10, but the cigarette portions are not so held, since the ports 10a are not yet in communication with the suction chamber. Consequently these cigarette 55 portions fall from the flutes into a suitable receptacle. Shortly after this, the ports 10 move away from the conduits 13, and the mouthpiece portion is released and falls from the flutes into another receptacle.

The case will now be considered in which either a 60 mouthpiece portion or a cigarette portion is missing from the group. As explained above, each group in turn is abutted by a pusher which advances the rearmost component while the foremost component is arrested by friction. Accordingly the incomplete group is fed forwardly, 65 as explained above, in such a way that its leading component cannot reach the stop member on the deflector, and as a result the incomplete group still has an endwise, forward component of movement when it reaches the suction drum 1. Here it is immediately gripped between the drum and the plate 2, which arrest its forward 70 movement, and in practice the incomplete group is found to be approximately centred on the drum 1, where it is united by a uniting band, or at any rate its position is such that when it is transferred as an assemblage to the suction drum 3, it will not extend over either of

the ports 10a. Consequently as soon as the ports 10, by which alone it is held, move away from the conduits 13, the incomplete assemblage will fall away.

It will be appreciated that in the case of an incomplete assemblage which is united by a uniting band, its rejection largely depends on the particular arrangement whereby the groups are abutted. Thus in order to obtain the greatest advantage from the detecting device, it is desirable to arrange the feeding of the groups in such a way as to ensure that only if a group is complete will the resulting assemblage register with the ports 10a as well as with the ports 10. It is to facilitate this that the ports 10 are located at the extreme ends of the drum 3 so as to be able to engage only the extreme end portions of a complete assemblage.

Although in the above description the device has been described in combination with a particular apparatus for feeding groups of cigarette portions and stubs, namely means for feeding them endwise and then deflecting them sideways, it could also if desired, be used with other apparatus by which for example, the cigarette portions and stubs are formed into groups and abutted endwise while moving sideways. In such a case the arrangement should preferably provide means whereby the cigarette portions of each group are urged towards each other, before the group reaches the suction drum 3, in such a way that should a stub or a cigarette portion be missing from the group, the incomplete group will become so positioned that when it reaches the drum 3 it will not extend over either of the ports 10a, and will then fall away when the ports 10 move away from the conduits 13.

The ports 10 and 10a are all brought into register with the groove 18 while the corresponding flutes 9 are empty, see Figure 1, and air is discharged outwardly through them, by way of the chamber 17 and groove 18, in order to blow away any tobacco dust or particles, or other matter which might clog the ports.

What I claim as my invention and desire to secure by Letters Patent is:

1. In apparatus for making mouthpiece cigarettes in which cigarettes and stubs arranged end to end in groups are united by adhesive encircling bands to form assemblages consisting of stub portions and cigarette portions, a device for testing the assemblages by supporting them at different positions along their lengths at different times, said device comprising supporting means for stub portions only and further supporting means for cigarette portions only, the two said supporting means being operative at different times and each being operative alone, so as to allow portions of an assemblage which have not

been united to other portions to fall away when not supported by one of said supporting means.

2. A device as claimed in claim 1, in combination with means for abutting the component parts of a group endwise before they are united, which means are so arranged as to cause an incomplete group to have a shorter overall length than a complete group and to cause it to be so positioned relatively to the supporting means as to be outside the range of action of at least one of them.
3. A device as claimed in claim 2, wherein the supporting means to support the cigarette portions of a complete assemblage consisting of two cigarette portions with a stub portion between them, are so positioned as to be capable of engaging such portions only near their extreme ends, whereby an incomplete assemblage, having a short overall length, can be positioned between the last mentioned supporting means so that they cannot support it.
4. A device as claimed in claim 1, wherein the supporting means comprise suction nozzles operable at different times, to support different parts of assemblages against the action of gravity.
5. A device as claimed in claim 4, wherein the suction nozzles are formed in a rotatable member which is arranged to transfer assemblages from apparatus in which they are united to apparatus on which they are cut, and wherein suction nozzles which engage different parts of an assemblage are put into and out of communication with a source of suction at appropriate different times.
6. In apparatus for making mouthpiece cigarettes in which cigarettes and stubs arranged end to end in groups are united by adhesive encircling bands to form assemblages consisting of stub portions and cigarette portions, and in which the groups are abutted endwise before they are united, a device for testing the assemblages, comprising support means so spaced apart as to be capable of engaging a complete assemblage near its extreme ends so as to constitute the sole support for such assemblages, and so located that an abutted assemblage from which one part is missing cannot be engaged by said support means and therefore falls away.
